United States Patent Office

Des. 214,776
Patented July 29, 1969

214,776

POWER OPERATED WRENCH

Raymond J. Schaedler, Utica, N.Y., assignor to Chicago
Pneumatic Tool Company, New York, N.Y., a corpo-
ration of New Jersey

Filed June 14, 1968, Ser. No. 12,362

Term of patent 14 years

Int. Cl. D8—02

U.S. Cl. D8—61

FIG. 1

FIG. 2

FIG. 3

FIG. 4

FIG. 5

FIG. 1 is a side elevational view of a power operated wrench showing my new design; the opposite side is the same;

FIG. 2 is a top plan view of FIG. 1;

FIG. 3 is a bottom plan view of FIG. 1;

FIG. 4 is a left end view of FIG. 1; and

FIG. 5 is a right end view of FIG. 1.

I claim:

The ornamental design for a power operated wrench, as shown and described.
